UNITED STATES PATENT OFFICE.

ABIGAIL REBECCA FULLER, OF CHICAGO, ILLINOIS.

DESIGN FOR A ROSETTE.

SPECIFICATION forming part of Design No. 16,887, dated September 7, 1886.

Application filed July 3, 1886. Serial No. 207,134. Term of patent 3½ years.

To all whom it may concern:

Be it known that I, ABIGAIL REBECCA FULLER, a citizen of the United States of America, residing at Chicago, in the county of Cook and State of Illinois, have invented and produced a new and original Design for an Article for Trimming, &c., of which the following is a specification, reference being had to the accompanying drawings, forming part thereof.

10 Figure 1 represents in plane my designed article in the form of rosette. Fig. 2 is an illustration of the same in folded position when raised in center; and Fig. 3 shows in side view and on enlarged scale a portion of the waved 15 surface of the article as designed.

My newly-designed article, as illustrated in the accompanying drawings, is intended to enrich the appearance of wearing apparel trimmed with the same. The article as presented in elevation is in form of a rosette, f, of circular shape, flat or raised in position, as shown in Figs. 1 and 2 of the drawings, displaying internal annular rows, b, of some selected material, in joint succession and corresponding configuration, for the purpose of enlarging or reducing the size of the article without altering the original design, and exhibits a ruffled or waved surface, c & a, when viewed in side elevation, as shown in Fig. 3, representing a fragmentary part of the same. The 30 end protuberance, a', at the circumference of the rosette is encircled by a garniture, b, in shape of a crown, as an auxiliary ornament, annexed and combined with the contour of the designed article, for the purpose of completing the configuration of the design and embellishing the same.

I claim—

A design for an article of manufacture for trimming, &c., the same representing a circular-shaped rosette displaying combined annular rows and a waved surface, said rosette having end protuberances, the same in combination with a garniture consisting of a crown-shaped ornament, substantially as illustrated 45 and specified, for the purpose set forth.

ABIGAIL REBECCA FULLER.
